UNITED STATES PATENT OFFICE.

HUGO ADERER, OF BLOOMFIELD, NEW JERSEY, ASSIGNOR TO J. F. JELENKO & COMPANY, A COPARTNERSHIP COMPOSED OF JESSE F. JELENKO AND HUGO ADERER, OF NEW YORK, N. Y.

ELECTROPLATING APPARATUS.

1,148,272.

Specification of Letters Patent. Patented July 27, 1915.

Application filed April 17, 1915. Serial No. 21,966.

To all whom it may concern:

Be it known that I, HUGO ADERER, a citizen of the United States, residing at Bloomfield, in the county of Essex and State of New Jersey, have invented certain new and useful Improvements in Electroplating Apparatus, of which the following is a full, clear, and exact specification.

This invention relates to electro-plating apparatus particularly adapted for use in plating a variety of articles of different shapes and sizes.

In plating a single shape and size of article, the proper plating current and electrode distance is determinable by calculation and experiment once and for all, but in plating various sizes of articles of different shapes the apparatus must be capable of ready adjustment to meet the varying kinds of work. 20 In dental and jewelers' work where much gold plating is done, the conditions vary with each piece of work and it is important to provide an easy and ready control of the voltage and electrode distance and to do this 25 with a minimum of time and attention on the part of the operator.

It is an object of this invention to provide such an electro-plating apparatus by providing adjustable electrode supports in series 30 with a lamp rheostat, the resistance setting of which may be observed from the glow of the filaments at a glance. The electrode arms are made adjustable to vary the relative position of the electrodes and the distance between them and consequently the resistance of the electrolyte and the rate and character of the metal deposit and it is possible to observe the amount and character of this adjustment by the varying glow of the 35 lamp filaments in series with the electrodes. In adapting the apparatus for occasional use with a variety of objects, the electrode supports have been made readily movable for the insertion and removal of the electrodes 40 from the electrolyte and back out of the way against their support and their adjustable mounting allows the electrolyte receptacle to be supported independently of the board and in no fixed relation to it. To avoid confusion in making the various adjustments, the 45 movements of the electrodes into and out of the electrolyte are arranged to be made in a vertical plane only and are distinct from the relative adjustments of the electrodes 50

within the electrolyte made preferably by movement of the anode horizontally.

In the drawings, Figure 1 is a perspective view of the apparatus, and Fig. 2 is a diagram of the board connections.

The board A of marble or other insulating 60 material is to be fastened in vertical position to a wall, and carries on its face the electrode supports B and C and the lamp rheostat D. The board is provided with a passage (not shown) for the entrance of the 65 supply wires and on its back it is provided with grooves (not shown) for the wires connecting the lamp and electrode arms as shown in Fig. 2.

Either support B or C may serve to carry 70 the anode or cathode plate. Preferably, the arm B by its holder jaws 4, 4 supports the proper anode or supply plate, 5, and the arm C by its jaws 6, 6 supports the hook 7, carrying the article 8, to be plated. The 75 jaws 4, 4, and 6, 6, are similar, being arranged to normally spring apart and being contractible to gripping engagement with the articles they carry by the slide loops 9 and 10, respectively. The jaws are fastened 80 at the upper ends in any convenient manner to the insulating handles 13 and 14. The jaws 4, 4, are pivoted horizontally to the link 15, at 16, and the link 15 is pivoted vertically at 17 to the link 18, which latter is pivoted 85 horizontally, as at 19, to the bracket 20 carried by the board A. The jaws 6, 6, like jaws 4, 4, are pivoted horizontally, as at 21, to the link 22 and link 22 is pivoted horizontally at 23 to the link 24, pivoted horizontally 90 at 25 to the bracket 26 carried by the plate A in spaced horizontal relation to bracket 20.

It is to be understood that, while any of the pivotal connections of arms B and C may be rigidly set by tightening the proper 95 pivot screw, they are of the adjustable friction type holding their various positions as set, yet movable by the hand of the operator. The electrode supports are themselves of a conducting material, as copper, and the frictional engagement of the double pivots reduces the contact resistance between them. Preferably, the support B carries the anode and the support C the cathode or article to be plated. By this arrangement, since the 100 linkages of support C are movable in a substantially vertical plane the operator is enabled to readily withdraw the article for in-

spection and replace it without disturbing the adjustment of the distance from the anode while the distance between the electrodes is controlled independently by swinging jaws 4, 4, carrying the anode horizontally around pivot 17. In this way the movement of the anode for adjustment is distinct and separate from the movement accompanying the insertion and withdrawal of the article and confusion between the two is avoided. The linkages of each support allow them to be folded back against the board when not in use and the electrolyte receptacle E may within certain limits be positioned at any convenient distance from the board B and yet be readily accessible to the electrodes by adjustment of the support links.

At the end of the board A opposite the supports B, C, the plug 29 carries the lamp socket 27. This socket is provided with electrical connections for varying the resistance and thereby the current of the circuit and the intensity of the lamp D. For this purpose, I preferably employ a lamp of the well-known "Hy-Lo" type, having a plurality of intensities. Thus by using two filaments 30, 31, singly, in series, or in parallel, four intensities can be obtained. The lamp base 28 contains suitable switches for securing these intensities, which are controlled by the cords 32, 33.

It will be seen that rather coarse adjustment of the voltage between the electrodes is provided by the lamp rheostat, and that intermediate adjustments are provided by varying the relative positions of the electrodes and that these intermediate adjustments in character and extent are readily observable in the varying glow of the lamp filament.

In practice, the electrode supports B and C are moved from their retracted positions against the board A and have positioned within their jaws 4, 4, and 6, 6, the anode 5 and cathode holder 7, respectively. The article 8 to be plated is then attached to the support C as by engagement with the hook 7 and the anode and article are immersed in a bath of the proper electrolyte, as a double cyanide of gold and potassium, contained in the receptacle B positioned on the support F at any convenient distance within the limits of the electrode support links and the two electrodes are adjusted to a proper distance to give an even deposit on the article. The lamp rheostat is set at a resistance to give the voltage necessary to carry on the plating at the desired rate and the current is turned on, the strength of the glow of the lamp indicating approximately the strength of the current. As the electro-plating progresses, the article is removed vertically from the electrolyte for inspection and the rate and evenness of the deposit may be con-

trolled as by re-positioning the electrodes in the bath by horizontal movement of the anode around pivot 17. If for a more even or compact deposit the distance between the electrodes is increased the filament glow 70 will fade and indicate the amount of the change effected and it will also indicate when the lamp resistance is to be decreased to compensate for the increased resistance of the electrolyte. If a more rapid deposit 75 is allowable, the distance between the electrodes may be decreased to increase the current and this increase may be gaged by the brightening of the filament glow which will also indicate when the rheostat resistance 80 must be increased to compensate for the decreased resistance of the electrolyte.

When not in use the electrolyte receptacle E is removed and the supports B and C are pushed back against the board A out of the 85 way of the operator. By simply placing the dish E within reach of the supports B and C and moving the supports to hold the electrodes within the electrolyte the apparatus is ready for use while the ease with which 90 the article may be inspected and the current and consequently the rate of deposit, controlled and observed particularly adapt the device for use by dentists, jewelers and others having need of an electro-plating device for occasional service, out of the way when not in use, yet readily accessible and easily and accurately adjustable to various kinds of work.

Having thus described my invention, I 100 declare that what I claim as new and desire to secure by Letters Patent, is:—

1. In an electro-plating apparatus, a board, a pair of electrode supports extending outwardly therefrom and relatively adjustable to vary the current between the electrodes, and a glow device mounted in circuit with said supports and in position to indicate by its intensity variations in the current through said supports. 110

2. In an electro-plating apparatus, the combination of a board carrying an electrode support, a second electrode support mounted on said board for vertical and horizontal adjustment with relation to the first support and a variable lamp resistance carried by said board for varying the voltage between the electrodes carried by the supports and indicating the current passing between said electrodes. 115

3. In an electro-plating apparatus, the combination with a supporting board, of an adjustable outwardly projecting electrode support having two horizontal pivots about which the electrode may swing in adjustment and a second outwardly projecting adjustable electrode support having one vertical and one horizontal pivot about which the second electrode may swing in adjustment. 125

4. The combination with a board, of out- 130

wardly projecting links pivoted thereto, depending anode and cathode terminals carried by said links, and means for varying the distance between said terminals.

5 5. The combination with a board, of outwardly projecting links pivoted thereto, depending electrode supports carried by said links, one of said supports being adjustable in a substantially vertical plane, and means 10 for varying the distance between said supports and between said supports and the board.

6. The combination with a board, of outwardly projecting links pivoted thereto, a 15 variable resistance lamp mounted on said board and in circuit with said links, depending electrode terminals carried by said links, and means for varying the distance between said terminals.

20 7. In an electro-plating apparatus, a

board carrying a contact bracket, a depending electrode support linked to said bracket to be movable toward and from the board, said electrode support comprising an operating handle at its upper end and electrode carrying means at its lower end. 25

8. In an electro-plating apparatus, a board carrying a contact bracket, a link pivoted thereon, a second link pivoted to said first link, and a depending electrode support intermediately pivoted to said second link, said electrode support having an operating handle at its upper end, and electrode carrying means at its lower end. 30

In testimony whereof I affix my signature, 35 in presence of two witnesses.

HUGO ADERER.
